ALARM SELECTOR APPARATUS

Louis Lucien Eugene Chauveau, Paris, France, assignor to Compagnie Generale de Telegraphie Sans Fil, Paris, France, a corporation of France

Original application November 19, 1928, Serial No. 320,397, and in France December 2, 1927. Divided and this application March 1, 1930. Serial No. 432,316

4 Claims. (Cl. 177—353)

It is well known that international commissions have been considering the addition to the S. O. S. distress signal of ships of another signal more particularly intended to actuate electromagnetic alarm selectors automatically, thus insuring a "distress watch" in the absence of the radio operator on the vessel. This new signal consists in sending out during say one minute intervals a predetermined series of dashes of four seconds separated by intervals of one second.

The present invention is a division of my pending application, Serial No. 320,397 filed November 19, 1928 entitled "Alarm selector apparatus" and relates to a selector device having as one of its objects the actuation of one or more suitable electric announcers as soon as a series of three consecutive dashes of four seconds duration, separated by intervals of one second have been recorded by the assembly comprising the radio receiver and the alarm selector.

The novel features which I believe to be characteristic of my invention are set forth with particularity in the appended claims.

My invention itself, however, both as to its organization and method of operation will best be understood by reference to the following description taken in connection with the accompanying drawing in which:

Fig. 1 represents diagrammatically one embodiment of the invention; and,

Fig. 2 represents diagrammatically a modification of the gearing system control means.

In Fig. 1 the reference mark A designates a wheel provided with a rotative movement at the rate of one revolution per second and with the facility to engage either the wheel RT, which will when engaged by A rotate at the rate of one revolution in 10 seconds, or with the wheel RE which will when engaged by A rotate at the rate of one revolution every two seconds. The start of the movement of wheel RT is fixed by the stop b and it comprises a shoulder e which is the means for closing the contact 18' at the end of the first second, the contact 14' at the end of the third second and the contact 17' at the end of the fifth second. These contacts are supported by extension of the support 50 not shown on the drawing. Relay 56 is connected to the output of any suitable receiver (not shown) in such a manner that upon receipt of a signal 56 is energized, arm y is pulled down to contact with x thus energizing relay MN'. Relay MN' acts on the lever of support 50 to engage RT with A.

If the dash received lasts less than a second the lever of support 50 is released by the relay MN',

the wheel RT thereupon due to the action of the spiral spring SR will return to its original position before the relays E₁, E₂, etc. of the recorder begin to function.

If the dash received lasts more than one second the contact 18' is closed by the shoulder e and the winding 20 of the slow-releasing relay TC is energized through 5', line L₁ contact 18' to minus. The contact 19 is then closed.

If the dash received lasts more than three seconds, that is, long enough to permit A to turn RT to such a position that the cam e closes 14' and approaches 17', the winding 21 of relay TC connected with contact 14' will be energized by the lines L₁, L₂. The winding 20 of relay TC opposes the winding 21. The winding 21 is energized by a circuit including the contact 18' in the closed position. To obtain the desired effect in this differential relay TC the contact 18' must remain closed until 14' is closed. This is insured by making the cam e on the wheel RT of sufficient arcuate length to span both contacts 18' and 14'. When the relay TC is so energized the contact 19 opens. TC is of the time lag type and the relay constants are such that the contact 19 will always be opened with a delay of about two-tenths of a second.

At the same time relay E₁ is energized over the circuit, positive upper contact of 5', contact 14', contact 13, winding of relay E₁, and negative at back contact of relay ZO. Relay E₁ at contact 22 connects negative to one terminal of silence magnet SL' and at its contact 12 closes a locking circuit for itself which may be traced from positive at contact 12, winding of relay AE₁, winding of relay E₁ and to negative at back contact of relay ZO. Relay AE₁ is not energized at this time since it is short-circuited by direct positive supplied to the winding of relay E through contacts 5', 14', and 13. When the impulses terminate the short circuit is removed and relay AE₁ energizes in series with relay E₁. Relay AE₁ when energized opens at 13 the original circuit for E₁ and at 14 switches contact 14' to relay E₂.

If the signal received lasts more than five seconds, the contact 17' is closed, whereupon the relay ZO is energized by way of the line L₁, LZ so that through its contact the circuits of all relays E₁, AE₁, E₂, AE₂ . . . etc. which may have been energized up to this moment are broken.

Assuming now that the first dash has been correct. The wheel RT after closing 14' is released by drive A and, under action of spring SR, returns to rest and the lever of its support imparts

plus terminal to the lower contact piece of contact 5'. Relay SL' is then energized since its circuit is prepared by the contact 22 of relay E₁ furnishing minus. The contact 19 is opened 5 and the relay ZO cannot enter into action. Relay SL' attracts the lever of support 51, wheel RE engages with the wheel A and if the silence 10 interval lasts more than two seconds the stop 52 closes contact 25' which imparts plus to the electromagnet ZO by means of lines L₆, LZ and the 15 relays of the recorder then come to rest.

If the interval lasts about a second or less, that is, is not long enough to permit 52 to close 25' before the next dash starts, the windings 56 and 15 MN' are energized and break the circuit through SL' at 5'. The wheel RE disengages from A and returns to rest without disturbing the circuits set up by the first dash of about four seconds duration.

20 The start of the movement of the wheel RE is fixed by the stop C, and it is returned to start position under the action of spring SR'. If the dash received lasts more than five seconds, the wheel RT will stop rotating since it is arrested 25 by its stop b which bears then against the inner edge of support 50. Wheel RE likewise stops turning for a silence longer than two seconds.

The springs 100 and 101 bring the supports 50 and 51 respectively back to the position of rest 30 when the relays MN' and SL' respectively are dead.

If the second or third dash received is too short, that is, over one second in length but less than about three seconds, the support 50 imparts a plus to the lower contact piece of contact 5', the contact 19 being then closed (the winding 20 of relay TC having been energized by way of 18' and being slow-acting does not open at once when the contact 5' leaves its upper 40 contact piece), the relay ZO receives plus by means of the lines LR, contact 19 and LZ and the apparatus is restored to normal.

During the return movement of the wheel RT, the closing of the contacts 18', 14' and 17' by the shoulder e is without effect since at that moment the line L₁ is not connected to the plus terminal since the contact 5' is located at its lower contact piece.

In analogous manner the second correct dash 50 energizes the relays E₂ and AE₂ and switches the line L₃ to L₄; the third correct dash energizes the relays E₃ and AE₃ and closes the circuit of the bell relay with its blocking contact 15 and contact 16, thereby closing the circuit of the bell SN 65 which will continue to ring until it is stopped by opening contact 15 in any desired manner. The selector is automatically brought back to zero by the first silence exceeding the duration of the first false signal following the closing of the bell circuit. The relay ZO then functions by virtue of the closing action of contact 17', 19 or 25', according to the case, and cuts off the energizing of all the relays, with the exception of the bell circuit which continues to function until the moment the contact 15 is opened. Opening of contact 15 may be accomplished by a push button contact PB between the selector and 15. When the line to 15 is broken by PB relay AE₃ becomes deenergized and contact 16 opens to silence the bell.

The wheel A may rotate either in constant manner driven by a motor or by a clock movement, or only at the moment of the reception of the signals. In this latter case the movement of the wheel A is controlled, either by the keying relay

MN', or by the silence relay SL' or again by a relay connected in series in a line common to the circuits of these two electromagnets.

Fig. 2 illustrates this latter embodiment. The wires connected to contacts 22 and x of Figure 1, instead of running directly to the negative pole of the battery as shown on this figure, are connected with each other and run to one of the terminals of relay C₁ whose other terminal is supplied by the negative. This relay controls a contact 23 which closes the circuit of a motor M driving the wheel A. It may also be the means for effecting the engagement of this wheel on a driving shaft. When signal energy comes in, at 56 contact x closes and MN' is energized in the same 80 manner as in the modification of Figure 1. At the same time C₁ is energized through the circuit C₁y, x and +. 23 closes the circuit through M and A starts to rotate at the same time lever 50 85 engages RT with A.

The constants of the duration of the dashes and the intervals may be modified by the modification of the dimensions or speeds of wheels RT or RE. In similar manner the number of elements of the recording group may be modified for 90 instance for the purpose of receiving signals composed of more than or less than three consecutive dashes.

I claim:

1. Selective signaling apparatus comprising indicating means, recording means for actuating the indicating means after the reception of a definite number of correct signals each of which has a duration fixed between two minimum and maximum limits identical for all the signals, the signals being separated by intervals which do not exceed a definite duration; a return-to-zero relay connected with the said recording means, a slow-releasing preliminary relay with two coils wound in opposition controlling a contact in the return-to-zero relay circuit, a rotary element, means controlled by the signal for causing uniform movement of this element in a definite direction and for simultaneously opening another contact in the return-to-zero circuit in series 105 with the first contact, and three contacts actuated by the rotary element during its uniform movement, the first of these contacts being actuated at the moment when the signal exceeds a limit which is fixed in advance, this first contact 110 being connected to one winding of the preliminary relay, the second of these contacts being actuated at the moment when the signal exceeds the minimum limit of the correct signals and being connected to the second winding of the preliminary 115 relay and with the recording means, and the third of these contacts being actuated at the moment when the signal exceeds the maximum limit of the correct signals, this contact being connected with the return-to-zero relay to cause 120 operation thereof independent of the slow-releasing relay.

2. Selective signaling apparatus comprising indicating means, recording means for actuating the indicating means after the reception of a definite 140 number of correct signals each of which has a duration fixed between two minimum and maximum limits identical for all the signals, the signals being separated by intervals which do not exceed a definite duration; a return-to-zero relay connected to the said recording means, a slow-releasing preliminary relay with two coils wound in opposition controlling a contact in the circuit 145 of the return-to-zero relay, a rotary element, means controlled by the signal for causing uni-

form movement of this element in a definite direction and for opening at the same time another contact in the return-to-zero circuit in series with the first contact, and three contacts actuated by the rotary element during its uniform movement, the first of the three contacts being actuated at the moment when the signal exceeds a limit which is fixed in advance, this first contact being connected to one winding of the preliminary relay, the second of these contacts being actuated at the moment when the signal exceeds the minimum limit of the correct signals and being connected with the second winding of the preliminary relay and with the recording means, and the third of these contacts being actuated at the moment when the signal exceeds the maximum limit of the correct signals, this contact being connected with the return-to-zero relay to cause operation thereof independent of the slow-releasing relay, a second rotary element, means, controlled by the silences following the first correct signal, for causing uniform movement of the second rotary element in a definite direction, and a contact, actuated by the said second rotary element at the moment when the silence exceeds the set limit, said contact being connected with the circuit of the return-to-zero relay.

3. In a selector apparatus responsive to a series of signal impulses of given duration, means for measuring the length of the received impulses comprising a displaceable member, a plurality of contact devices arranged in the path of

displacement of said member and at predetermined distances from each other, means responsive to the signal impulses for displacing said member along its path to successively actuate said contact devices, a slow releasing relay, means controlled by the actuation of one of the contact devices upon the receipt of an impulse of a given duration less than said given duration for energizing the slow releasing relay, a second relay device, means controlled by the actuation of a succeeding contact device upon receipt of a signal impulse of the said first mentioned duration for energizing the second relay device and also counteract the energization of the slow acting relay, a third relay device, means controlled by the second relay device for maintaining itself energized and for associating said second mentioned contact device with the third relay, an alarm associated with the third relay device, means for restoring the second and third relay devices, and means controlled by said slow releasing relay when not counteracted by the closure of the second mentioned contact device in combination with means controlled by the termination of the impulse when the impulse is of duration between the first and second given duration for operating said restoring means.

4. The system as claimed in claim 3, in combination with means responsive to a signal lasting longer than the first mentioned duration for operating said restoring means.
